UNITED STATES PATENT OFFICE.

CHARLIE W. BARZEE, OF PORTLAND, OREGON.

ROTARY PUMP.

1,259,460.

Specification of Letters Patent. Patented Mar. 12, 1918.

Application filed September 18, 1916. Serial No. 119,911.

To all whom it may concern:

Be it known that I, CHARLIE W. BARZEE, a citizen of the United States, residing at Portland, in the county of Multnomah and State of Oregon, have invented certain new and useful Improvements in Rotary Pumps, of which the following is a specification, reference being had to the accompanying drawings.

10 This invention relates to certain improvements in pumps and has relation more particularly to a rotary pump wherein is employed a rotor provided with a plurality of substantially radially movable blades; and 15 it is an object of the invention to provide a pump of this general character having novel and improved means whereby the rotor together with the blades thereof may be operated with a minimum of eccentric 20 friction and at the same time affording a maximum of water space.

The invention consists in the details of construction and in the combination and arrangement of the several parts of my improved pump whereby certain important advantages are attained and the device is rendered simpler, less expensive and otherwise more convenient and advantageous for use, all as will be hereinafter more fully set forth.

The novel features of the invention will hereinafter be definitely claimed.

In order that my invention may be the better understood, I will not proceed to describe the same with reference to the accompanying drawings, wherein—

Figure 1 is a vertical sectional view, with parts in elevation of a pump constructed in accordance with an embodiment of my invention;

Fig. 2 is a vertical sectional view of the rotor as herein embodied, the operating shaft coacting therewith being shown in fragment;

Fig. 3 is a sectional view taken substantially on the line 3—3 of Fig. 1;

Fig. 4 is a view in top plan of the upper head for the casing as herein disclosed; and

Fig. 5 is a view in top plan of the shaft disposed within the rotor together with the plate coacting with the upper end thereof.

As disclosed in the accompanying drawings, 1 denotes the casing of my improved pump of predetermined dimensions supported by and connected to the lower end

of the discharge pipe 2 through the medium of the coupling 3.

The opposite ends of the casing 1 are closed by the heads 4 and 5 and a marginal portion of the upper head 4 is cut away, as at 6, to afford a discharge or outlet for the chamber created between the heads 4 and 5. The portion of the chamber immediately below the cut-away portion 6 is gradually enlarged, as indicated at 7, in the same general direction as the direction of rotation of the rotor R positioned within the chamber between the heads 4 and 5 with the base 8 of said enlargement disposed on a predetermined incline so that as the rotor R is operated, the blades B coacting with the rotor will serve to lift the water through the discharge 6, said water being received within the casing 1 between said heads 4 and 5 through the ingress opening 9 suitably positioned in a side wall of the casing 1.

The upper head 4 is of a dome formation with the lower or open marginal portion thereof provided with the annular groove 80 or channel 10 in which is snugly fitted the upper portion of the rotor R which rotor is hollow and cylindrical in cross section and closed at both ends. The rotor is provided with a top head 11 extending upwardly within the chamber afforded by the dome formation of the upper head 4 and said top head 11 of the rotor R is keyed or otherwise affixed to the lower extremity of the operating shaft 12. The shaft 12 extends upwardly through the discharge pipe 2 and is adapted to be driven in any desired manner in order that the requisite rotation may be imparted to the rotor R.

The lower head 14 of the rotor R is provided with the opening 15 which snugly receives the upstanding portion, lug, or bearing, 16 carried by the lower head 5 of the casing 1 concentric to the shaft 12 and which affords a mounting for the lower end portion of the rotor R, causing the rotor R to become, virtually, an enlarged continuation of the shaft 12 with a bearing at either end thereof, the hollow inside of the rotor R being reserved or used for the operation of the blades B.

Interposed between the heads 5 and 14 is an anti-friction means generally indicated at A, and which may be of a construction as may best meet the requirements of prac-

tice in order to assure the rotation of the rotor R with a minimum of frictional resistance.

The rotor R through the medium of the heads 11 and 14 affords an inclosed chamber C, and disposed longitudinally thereof and at a point eccentric to the axial center of the rotor is the stationary shaft 17 herein disclosed as an elongated member cylindrical in cross section and disposed through the lower head 5. Coacting with the lower end of the shaft 17 and the lower head 5 is the clamping nut 18 while the upper end portion of the shaft 17 is provided with the extension 19 substantially semi-circular in cross section and which is snugly received within a corresponding opening 20 produced in the plate 21. The plate 21 is provided with an upstanding lug or stub shaft 22 circular in cross section and which is disposed within a corresponding recess or socket 23 produced in the lower end of the operating shaft 12 at the axial center thereof. By this arrangement it will be perceived that the plate 21 serves as a rest or support for the upper end portion of the shaft 17 and also holds the same against rotation or turning movement as the upstanding lug or stub shaft 22 is eccentric to the opening 20.

The blades B are disposed radially of the rotor R and extend within the chamber C of said rotor and are also of a length substantially equal to the length of the rotor.

In practice I have found it of particular advantage to have said blades eight in number with the same arranged in four pairs, the blades of each pair being diametrically opposed and provided at their rear margins with the longitudinally spaced arms 24, each pair of alined arms being operatively connected with an elongated eye 25 through which the shaft 17 extends, said eye being elongated with its major axes disposed perpendicular to the pair of coacting blades B. As is particularly illustrated in Fig. 1 it is to be noted that adjacent arms 24 and eyes 25 are substantially in contact one with the other, whereby the strength of the eyes is materially increased. It is thought to be self-evident that the position of the shaft 17 and the coaction of the eyes 25 are such as to maintain the blades B constantly in contact with the inner walls of the casing 1.

Whereby it will be obvious that as the rotor R is revolved the fluid entering the casing through the ingress opening 9 will be lifted through the discharge 6.

It is to be noted that one pair of alined arms is arranged adjacent the longitudinal center of the coacting blades while the second pair of alined arms is arranged adjacent an end portion of the blades. By this arrangement it has been fully demonstrated that the blades B may be materially

longer and that this particular arrangement of the alined arms 24 serves effectually to prevent twisting strain upon the blades relative to the shaft 17.

While my invention has been hereinbefore set forth in connection with a rotor revolving about a vertical axis, for drilled or deep well pumps, it will be understood that my invention can be employed with equal facility in connection with a pump 75 wherein the rotor revolves about a horizontal axis suited to a suction lift and discharge elevation by means of pipes attached to the outer casing 1 for ingress and egress of the fluid on opposite sides of the cut off made 80 by means of the rotor coming in close contact with the outer casing between the ingress and egress pipes attached thereto. As this construction is thought to fairly fall within my invention as claimed, a detail description and illustration thereof is believed to be unnecessary.

From the foregoing description, it is thought to be obvious that a pump constructed in accordance with my invention 90 is of an extremely simple and comparatively inexpensive nature and is particularly well adapted for use by reason of the convenience and facility with which it may be assembled, and it will also be obvious that my invention 95 is susceptible of some change and modification without material departure from the principles and spirit thereof and for this reason I do not wish to be understood as limiting myself to the precise arrangement 100 and formation of the several parts herein shown in carrying out my invention in practice, except as hereinafter claimed.

I claim:

1. A rotary pump comprising a casing, a hollow rotor mounted within the casing, means for rotating the same, blades disposed radially of the rotor and extending therein, said blades coacting with the casing, a shaft disposed within the rotor through an end thereof and eccentric to the axis of said rotor, said blades having coacting therewith eyes through which the shaft is disposed, and a plate coacting with the opposite end of the rotor and the shaft for maintaining the shaft in applied position, said plate being provided with a lug extending within the adjacent end of the rotor at the axial center of the rotor.

2. A rotary pump comprising a casing, a hollow rotor mounted within the casing, means for rotating the same, blades disposed radially of the rotor and extending therein, said blades coacting with the casing, a shaft disposed within the rotor through an end thereof and eccentric to the axis of said rotor, said blades having coacting therewith eyes through which the shaft is disposed, and a plate coacting with the opposite end of the rotor and the shaft for maintaining

the shaft in applied position, said plate serving to hold the shaft in applied position.

3. A rotary pump comprising a casing, a hollow rotor mounted within the casing, means for rotating the same, blades disposed radially of the rotor and extending therein, said blades co-acting with the casing, a shaft disposed within the rotor through an end thereof and eccentric to the 10 axis of said rotor, means for securing the shaft to the casing, said blades having co-acting therewith eyes through which the shaft is disposed, and a plate co-acting with the opposite end of the rotor and the shaft 15 for maintaining the shaft in applied position, said plate being provided with a lug extending within the adjacent end of the rotor at the axial center of the rotor.

4. A rotary pump including a casing provided with an ingress opening and a discharge opening, the portion of the casing immediately below the discharge opening being gradually enlarged with the base of said enlargement disposed on a predetermined 20 incline, a rotor positioned within the casing, means for rotating the rotor, blades disposed radially of the rotor and co-acting with the casing, said blades being arranged in pairs, the blades of each pair being connected one to the other at two points 25

30

spaced longitudinally of the blades, each of the connections between the blades being formed into an elongated eye, said rotor being hollow and a shaft extending within the rotor and eccentric to the axis thereof 35 and disposed through the eyes.

5. A rotary pump including a casing provided with an ingress opening and a discharge opening, a hollow cylindrical rotor positioned within the casing and closed at 40 opposite ends, one end of the rotor being provided with an opening, a bearing carried by the adjacent wall of the casing and snugly fitting within the opening in the end of the rotor, a fixed shaft carried by the 45 bearing and extending within the rotor at a point eccentric to the axial center of the rotor, an operating shaft fixed to the second closed end of the rotor, blades extending radially of the rotor and extending therein, 50 said blades co-acting with the casing, said blades having co-acting therewith eyes through which the shaft within the rotor is disposed.

In testimony whereof I hereunto affix my 55 signature in the presence of two witnesses.

CHARLIE W. BARZEE.
